CLAIM

The ornamental design for an isolation gown with surface ornamentation, as shown and described.

DESCRIPTION

FIG. 1 is a front elevation view of an isolation gown with surface ornamentation, showing our new design; and, FIG. 2 is a detailed front view of a portion from FIG. 1 thereof.

The evenly spaced broken lines shown in the drawings depict portions of the isolation gown with surface ornamentation that form no part of the claimed design.

The dash-dot-dash broken lines shown in the drawings indicate the sectional detail view of the claimed design and form no part thereof.
